UNITED STATES PATENT OFFICE.

FRÉDÉRIC AUGUSTIN POLLARD, OF PARC ST. MAUR, FRANCE.

APPARATUS FOR REFRIGERATING BY MEANS OF LIQUEFIED GAS.

1,091,957.

Specification of Letters Patent. Patented Mar. 31, 1914.

Application filed March 23, 1911. Serial No. 616,398.

To all whom it may concern:

Be it known that I, FRÉDÉRIC AUGUSTIN POLLARD, of 24 Rue Lucie, Parc St. Maur, Seine, France, engineer, have invented a new and useful Improvement in Apparatus for Refrigerating by Means of Liquefied Gas, which improvement is fully set forth in the following specification.

This invention has for its object an arrangement for refrigerating by means of liquefied gases such as carbonic acid, ammonia, methylchlorid, sulfurous acid or the like which comprises in the known manner, a compressor driven by an engine and connected to a condenser and to a refrigerator, and an auxiliary pump. According to this invention the same gas, raised to a sufficient pressure, is employed to generate the motive power necessary to drive the compressor. The advantage of this arrangement is that the compressor can be coupled to its engine and both can be inclosed within a gas tight casing comprising one joint only or very few joints. All outward leakage of gas is thus avoided which usually takes place through the many joints in the compressor and above all through the stuffing boxes of the piston rods.

My invention is embodied in the means, arrangements and combinations of parts hereinafter described and more particularly pointed out in the claim.

In the accompanying illustrative drawing Figures 1 and 2 show diagrammatically two ways of carrying out the invention. Fig. 3 is a vertical section of a portion of an engine and compressor to a larger scale. Fig. 4 is a partial horizontal section through the axis of the distributor. Fig. 5 is a section on the line A—A in Fig. 3. Figs. 6 and 7 are partial sections on the lines B—B and C—C in Fig. 3.

In Figs. 1 and 2, 1 is a generator feeding through the pipe 2 an engine 3 with gas at high pressure. The engine 3 is directly coupled to a compressor 4 and to an auxiliary pump 5, all three members being inclosed within a single gas tight casing 6. The engine and compressor may be coupled in any known manner and may comprise either a single piston one of whose faces is used to drive and the other to compress, or a rod common to two pistons one of which drives and the other compresses or a shaft common to the connecting rods of two pistons or a rotary arrangement as illustrated in the

drawings. The compressor 4 delivers and the engine 3 exhausts through a pipe 7 into a single condenser 8 of any known type. The engine should therefore be adapted to work so that the pressure at the end of expansion is nearly equal to that in the condenser. The auxiliary pump 5 aspirates a portion of the gas liquefied in the condenser through the pipe 9 and delivers it to the generator through the pipe 10. 11 is a cock on the pipe 12 for supplying as is usual liquefied gas to the refrigerator 13.

In Fig. 2 the pump 5 and the cock 11 have been replaced by a pump 5 coupled directly to the engine and compressor in the casing 6 which through suitably arranged distributing passages and the pipes 10 and 12 serves simultaneously to feed the generator 1 and the refrigerator 13 with liquefied gas. The pump 5 serves to measure the quantity of liquefied gas delivered to the refrigerator while avoiding the use of a possibly leaky cock 11. From the refrigerator 13 the expanded gas passes through the pipe 14 to the compressor 4.

Figs. 3 to 7 illustrate the combination of an engine, a compressor and a pump such as shown diagrammatically in Fig. 2. It consists of a gas tight rotary mechanism having cylindrical pistons for which application for patent Serial No. 615,884 has already been filed in the United States on March 21st, 1911. The three parts: viz. an engine (comprising cylinders 15) a pump (comprising a cylinder 17) and a compressor (comprising cylinders 16) are located within the same gas tight casing 18. The cylinders 15, 16 and 17 are fixed at one end to a conical sleeve 19 which turns upon a conical journal 20 which serves at the same time as a distributor. The pistons 21, 22 and 23 are fixed to axes 24 carrying rollers 25 which move in circular grooves 26 eccentric with respect to the axis of rotation of the cylinders, in such a manner that the pistons describe a circle whose center is at a distance from the center of rotation of the cylinders equal to the length of the imaginary cranks actuating the sleeve 19 forming the driving shaft. Gas tightness between the cylinders and the distributing journal is obtained by the pressure of springs 27 exerted upon an axial ball bearing 28. The journal 20 is provided with suitable admission and exhaust passages, and aspiration and delivery passages arranged to obtain the necessary

degrees of expansion or compression. Admission to the driving cylinders 15 takes place through the pipe 29 and the passage 30 with which the journal 20 is provided. 5 Exhaust from the engine, in common with the delivery from the compressor, takes place through the passage 31 in the distributing journal and through the pipe 32. Aspiration to the compressor (cylinders 16) 10 takes place through the pipe 33 and the passage 34 in the journal. Ports 35 and 36 place the ends of the cylinders 15 and the end of the cylinders 16 in communication successively with the admission (aspiration) 15 and with the outlet (delivery). Aspiration to the cylinder 17 and the auxiliary pump takes place through the pipe 37 and the passage 38 in the journal; delivery from the pump to the generator takes place through 20 the passage 39 and the pipe 40, delivery from the pump to the refrigerator through the passage 41 and the pipe 42.

Claim.

25 In an apparatus for refrigerating by means of liquefied gas, the combination with an engine driven by the same gas, a com-

pressor and a pump directly coupled to the engine, and a casing provided with interior eccentric grooves and entirely inclosing the engine, the compressor and pump, the said engine, compressor and pump comprising radiating cylinders, of a sleeve provided with distributing ports, to which said cylinders are fixed, a hollow shaft provided with distributing ports registering with the first-named ports, on which said sleeve is mounted, and pistons arranged in the cylinders and provided with cross-pieces engaging the eccentric grooves in the casing, a generator for raising the pressure of the gas before delivery to the engine, a condenser supplied with gas derived from the engine and compressor and a pump adapted to deliver gas from said condenser to the generator.

40 In testimony whereof I have signed this specification in the presence of two subscribing witnesses.

FRÉDÉRIC AUGUSTIN POLLARD.
